UNITED STATES PATENT OFFICE.

GUSTAV SCHULTZ AND FRITZ GEHRE, OF MUNICH, GERMANY, ASSIGNORS TO EMILIO BLECHER AND CARLO LOPEZ, OF HAMBURG, GERMANY, AND CARL DISTLER, OF MUNICH, GERMANY.

EXPLOSIVE COMPOUND.

No. 894,707.

Specification of Letters Patent. Patented July 28, 1908.

Application filed January 25, 1906. Serial No. 297,832.

To all whom it may concern:

Be it known that we, GUSTAV SCHULTZ and FRITZ GEHRE, subjects of the King of Bavaria and Emperor of Germany, residing at, respectively, No. 3 Geselastrasse, Munich, Bavaria, Germany, and No. 8 Blutenstrasse, Munich, Bavaria, Germany, have invented certain new and useful Improvements in Explosive Compounds; and we do hereby declare 10 the following to be a full, clear, and exact description of the invention, such as will enable others skilled in the art to which it appertains to make and use the same.

This invention relates to safety explosives 15 of high shattering power, and is based upon the observation that bi- and tri- nitro-derivatives of tri-methyl-benzene (pseudocumol or mesitylene) in combination with suitable solid, inorganic, oxidizing salts, constitute 20 an excellent safety explosive of a very high shattering power, which has not been attained by the well-known explosives formed by the combination of various nitro compounds of aromatic hydro-carbons with 25 suitable substances which easily give up oxygen.

In making our new compounds we combine the bi- or tri-nitro compounds obtained 30 by nitration of pseudocumol or mesitylene with suitable solid inorganic oxidizing salts, such, for instance, as ammonium nitrate; and to increase the shattering power of such compounds we add thereto finely powdered iron or copper. The best results have been obtained 35 by using the following proportions:—

Twelve parts by weight of the bi- or tri-nitro tri-methyl-benzene or of a mixture of both are mixed with eighty-eight parts of ammonium nitrate. If an explosive of a very high shattering power be required, then preferably twelve parts of the nitro- bodies are mixed with eighty-six parts of ammonium nitrate and two parts of powdered copper or iron, or a mixture of these metals is added.

It is to be understood that we do not wish to be limited to the use of the ammonium nitrate as an oxidizing agent, as other oxidizing agents, used previously for the same purpose in combination with various other nitro-compounds of aromatic hydro-carbons, such as alkali nitrates, chlorates and the like may be used.

We claim as our invention:

1. A safety explosive compound, consisting of a mixture of bi- and tri-nitro derivatives of tri-methyl-benzene with a solid inorganic oxidizing salt.

2. A safety explosive compound, consisting of a mixture of bi- and tri-nitro derivatives of tri-methyl-benzene with a solid inorganic oxidizing salt and finely powdered iron and copper.

In testimony whereof we have hereunto set our hands in the presence of two subscribing witnesses.

GUSTAV SCHULTZ.
FRITZ GEHRE.

Witnesses:

FR. HUGO JACOBS,
WILLY KOLHAUS.
